UNITED STATES PATENT OFFICE.

LEWIS PETRIK, OF CALDWELL, TEXAS.

WELL BUCKET.

Application filed November 3, 1924. Serial No. 747,593.

To all whom it may concern:

Be it known that I, LEWIS PETRIK, a citizen of the United States, residing at Caldwell, in the county of Burleson and State of Texas, have invented certain new and useful Improvements in Well Buckets, of which the following is a specification. This invention relates to improvements in well buckets, and has for its principal object to provide a flat valve, in connection with the water inlet provided in the bottom of the bucket, the same being of such construction as to permit water to enter the bottom of the bucket, when the same is lowered into a well, and further permitting the closing of the filling opening during the upward pulling of the bucket from the well.

A further object of the invention is to provide a well bucket of the above-mentioned character, which is of such construction as to prevent the sediment which oftentimes enters the bucket when the water in the well is very low, from preventing the closing of the flat valve, so that the water in the bucket will not leak through the opening, during the upward movement of the bucket.

A further object is to provide a well bucket of the above mentioned character, wherein the valve associated therewith may be readily disassembled and removed whenever it becomes necessary.

A still further object is to provide a well bucket of the above mentioned character, which is simple in construction, inexpensive, strong and durable, and further well adapted for the purposes for which it is designated.

Other objects and advantages of this invention will become apparent during the course of the following detailed description.

In the accompanying drawing, forming a part of this specification, and in which like numerals designate like parts throughout the same:

The figure represents a vertical sectional view, through the well bucket embodying my invention.

In the drawing, wherein for the purpose of illustration is shown the preferred embodiment of my invention, the numeral 1 designates the lower portion of a well bucket, the bottom 2 thereof being provided with an enlarged centrally located opening 3. An internally threaded sleeve 4 is adapted to extend through the opening. An annular flange 5 is formed on the lower end

of the sleeve, and the same is adapted to be secured to the bottom 2 of the bucket 1, by any suitable fastening means, shown at 6. A short piece of pipe 7 is threaded at its lower end into the internally threaded sleeve 4 and extends upwardly into the bucket. The upper end of the pipe 7 is ex-

ternally threaded, and supports thereon the internally threaded sleeve 8. The latter is provided with an annular flange 9, on the upper edge thereof, and an extension 10 is formed on the annular flange, as clearly illustrated in the drawing.

A flat valve 11, which is formed of a suitable piece of leather is of substantially the same shape as the annular flange 9, and the extension 10 formed thereon, and the portion of the flat valve, which extends over the extension 10 is secured thereto by the fastening bolts 12. For the purpose of normally holding the flat valve 11 seated over the upper end of the pipe 7, a weight, such as is shown at 13, is secured to the flat valve by the fastening means 14. The upward swinging movement of the flat valve 11 and the weight 13 carried thereby is limited by the provision of the stop 15, which comprises an angular piece of metal, and is further secured on the extension 10 of the annular flange 9, by the fastening means 12, as clearly illustrated in the drawing.

In use, the bucket 1 is lowered into the well and upon the bottom of the bucket coming in contact with the water in the well, the water pressure will raise the flat valve 11, upwardly out of engagement with the upper edge of the pipe 7, permitting the bucket to be filled with water from the well. After the bucket has been filled, the same is raised upwardly, and the flat valve will be seated over the upper end of the pipe 7, thereby preventing any of the water in the bucket from escaping therethrough. The flat valve is supported on the upper end of the pipe 7, in such a manner as to prevent any possibility of the sediment, which may flow into the bucket, with the water, from preventing the closing of the flat valve, such as frequently happens with the well buckets now in use.

The simplicity in which my well bucket is constructed, enables the parts to be readily disassembled whenever it becomes necessary to remove the same from an old and worn out bucket. The valve is preferably constructed from steel, whereby the same is rendered strong and durable.

While I have shown the preferred embodiment of my invention, it is to be understood that various changes in the size, shape, and arrangements of parts may be resorted to, without departing from the spirit of the invention and the scope of the appended claims.

Having thus described my invention, what I claim is:

10 1. A well bucket having an opening in the bottom thereof, an internally threaded sleeve extending through said opening, a flange on the lower end of the sleeve adapted to be secured to the bottom of the bucket, a short 15 piece of pipe threaded at its lower end into said sleeve and extending upwardly in said bucket, and a flat valve carried by the upper portion of the pipe and normally disposed over the upper end of the same, to prevent the escape of the water in the bucket through the pipe.

20 2. A well bucket having an opening in the bottom thereof, an internally threaded sleeve extending through said opening, a flange on the lower end of the sleeve adapted to be secured to the bottom of the bucket, a short 25 piece of pipe threaded at its lower end into

said sleeve and extending upwardly in said bucket, an additional sleeve supported on the upper end of the pipe, an annular flange formed on the upper end of the sleeve, a flat valve secured at one end to said flange and normally disposed over the upper end of the pipe for keeping the same closed.

3. A well bucket having an opening in the bottom thereof, an internally threaded sleeve extending through said opening, a flange on the lower end of the sleeve adapted to be secured to the bottom of the bucket, a short piece of pipe threaded at its lower end into said sleeve and extending upwardly in said bucket, an additional internally threaded sleeve threaded on the upper end of the pipe, an annular flange formed on the upper end of the sleeve, and extensions on said flange, a weighted flat valve secured on said extension and normally disposed over the upper end of the pipe, for keeping the same closed, and means associated with the extension, for limiting the upward swinging movement of the flat valve.

In testimony whereof I affix my signature.

LEWIS PETRIK.
